UNITED STATES PATENT OFFICE.

HARVEY W. BELL, OF YONKERS, NEW YORK, ASSIGNOR TO THE BELOYT CORPORATION, OF DOVER, DELAWARE, A CORPORATION OF DELAWARE.

UNIVERSAL JOINT.

Application filed January 11, 1921. Serial No. 436,434.

To all whom it may concern:

Be it known that I, HARVEY W. BELL, a citizen of the United States, and a resident of Yonkers, Westchester County, and State of New York, have invented certain new and useful Improvements in Universal Joints, of which the following is a specification.

My present invention has for its general objects to simplify and improve the construction of universal joints and further to increase the flexibility and durability of devices of this character.

These objects I have attained in the construction disclosed in the accompanying drawing which illustrates but one of the forms the invention may take.

Figure 1 is a face view of the joint with the near length of shafting appearing in section.

Figure 2 is a cross sectional view taken on substantially the plane of line 2—2 of Figure 1 and with the two sections of connected shafting indicated as broken away.

Figure 3 is a side elevation of the joint as shown in Figure 1.

Figure 4 is a detail view on a smaller scale of a preferred form of flexible connecting means.

Figure 5 is a cross sectional view of one of the clamps taken on substantially the plane of line 5—5 of Figure 1.

Figure 6 is a face view of one of the clamping elements.

In Figure 2 I have shown at 10 and 11 two sections of shafting connected by the universal joint. Affixed to the shaft section 10 is a collar 12 having radially extending diametrically opposite outstanding arms 13, 14 and similarly, the shaft section 11 has affixed to it a collar 15 carrying diametrically opposite radially extending arms 16, 17.

Each of the radial arms described terminates in a clamp element 18, with which cooperates a cap or companion clamp element 19 held by a securing bolt 20.

A special feature of these cooperating clamp elements or jaws 18, 19 is that they are arranged on radial lines, as indicated at 21 in Figure 1.

Engaged between the clamping jaws are strips 22 of suitable connecting fabric, such as rubber impregnated canvas belting and in

order to better hold the ends of the strips in the clamps, I have shown the faces of the clamps as corrugated, as at 23 in Figure 6, 55 a special feature of these corrugations being that they also are arranged on radial lines, the same as the jaws, as will be clear from Figure 1.

In Figure 4 I have shown how the strips 60 of connecting medium form in effect a quadrangular figure, the ends of the strips being cut diagonally as at 24 to abut on radial lines, the force of the clamps being sufficient to secure the abutting strips in 65 this relation. To provide the necessary strength, the strips may be built up in a number of different layers, as I have indicated in Figures 2 and 3.

The joint of this invention will be seen to 70 be both simple and practical, an especially important point being that no lubrication is required and that while the joint is extremely flexible, the twisting of the connecting medium at any one point is so slight as to cause 75 no injury or appreciable wear. This added flexibility and wearing quality is due in large part to the radial arrangement of the clamping faces which are thus enabled to transmit the load to the flexible connecting 80 medium without straining or twisting any one part more than another part. In other words, the load is carried to the fabric practically evenly on lines substantially at right angles to the lines of applied force. The 85 construction, it will be seen, also provides for reversal of power, the joint being operative to drive as well in both directions.

While the two-armed spider construction illustrated gives the greatest flexibility, it is 90 possible that under certain conditions, three or more armed spiders might be preferable. My invention, therefore, contemplates this and other modifications of the structure and I further wish it understood that the terms 95 employed herein are used in a descriptive rather than in a limiting sense, except for such limitations as may be required by the prior art.

What I claim is:

1. In a universal joint, strips of flexible fabric arranged end to end in the form of a polygon, the adjoining ends of the several strips being angled to fit closely together in

substantially abutting relation, a coupling member having arms carrying clamps each engaging end portions of two adjoining strips, and a second coupling member having arms carrying clamps each engaging other end portions of adjoining strips.

2. The structure of claim 1 in which the

clamps are angled to fit the corners formed by the abutting strips and each extend across the full width of both abutting strips.

In witness whereof, I have hereunto set my hand this 10th day of January, 1921.

10

HARVEY W. BELL.
